UNITED STATES PATENT OFFICE.

ARTHUR JOHN HENRY ARTHUR, OF ADELAIDE, SOUTH AUSTRALIA, AUSTRALIA.

CROSS-SECTIONAL CLINOMETER.

1,393,419.

Specification of Letters Patent. Patented Oct. 11, 1921.

Application filed January 27, 1919. Serial No. 273,414.

To all whom it may concern:

Be it known that I, ARTHUR JOHN HENRY ARTHUR, a citizen of the Commonwealth of Australia, residing at Adelaide, in the State 5 of South Australia, have invented a new and useful Cross-Sectional Clinometer, of which the following is a specification.

My invention relates to an improved clinometer, the object of the same being to 10 provide a graduated implement wherein the various parts are so arranged as to enable field work to be accurately set out with greater ease than is at present the case.

My invention is more particularly de- 15 signed for use in connection with railway and road work and when applied as herein-after explained will enable pegs to be inserted either for cuttings or embankments with great speed and accuracy.

20 In order to achieve the object of my invention, I construct a vertical pillow which acts as a foundation for the instrument and upon which I mount a vertical slide block above which there is a horizontal sliding 25 bed for supporting a batter rod. I also provide a telescope mounted upon an axis and designed to operate in conjunction with a graduated quadrant, the end of the telescope being fitted with a graduated extension, and 30 a level and reflectors being inserted in the structure to enable the bubble of the level to be easily seen. These several parts are ad- justed and clamped and enable the necessary 35 positions of the pegs for a cutting or a filling to be easily ascertained.

In order that my invention may be more clearly understood, I will now proceed to describe the same by aid of the accompanying 40 illustrative drawings wherein,

Fig. 1 is a front elevation of the instrument.

Fig. 2 is a rear view of same.

Fig. 3 shows interlocking members for foundation block.

45 Figs. 4 and 5 illustrate method of mounting the level.

Fig. 6 is a diagram to illustrate the method of plotting a cross section.

Fig. 7 is another diagram illustrating the 50 operation of the device for obtaining the cubic contents of a cut or fill.

In each of the illustrations similar letters of reference are used to denote similar or corresponding parts wherever they occur.

55 In the drawings, *a* is a vertical pillar the bottom portion of which is slotted or

grooved at *b* for the support of a vertical slide block *c* which is clamped in position by means of a clamp screw *d*; vertical graduations are provided as shown in 60 Fig. 2 of the drawings. The telescope *e* is pivotally mounted on the pillar so that it rotates upon the axis *f*, an arcuate slotway being cut at *g* for guide purposes and to clear the level mountings. 65

Upon the telescope, wing plates or straight edges *h* are formed and are superimposed above the graduated telescope quadrant *j*, the graduations of the quadrant being from zero degrees to zenith and from 70 zero degrees to nadir, the straight edges being formed at an angle of forty five degrees from the axis point *f* when the telescope is set as a true horizon thus representing the 75 limits of a quadrant of ninety degrees, and to enable the telescope to be so set, I provide therein a level *k*, and in order that the level may be easily watched I provide mirrors or reflectors at *l*, mounted on the inner side of the left hand side of the casing and set at 80 suitable angles as illustrated.

The level which is mounted on the vertical cylinder is inside the sighting tube and its bubble can be viewed without the aid 85 of the mirrors when the tube is at an inclination of a few degrees either side of zero and simultaneously with a staff in the field.

The sight or aperture of the telescope is situated at *m*, and on the opposite end, the instrument extends rearwardly with a graduated extension rod *n*, the graduated edge of which is in alinement with the axis *f*, the center point of which is zero. At right angles to the vertical pillar and beneath the telescope, but also extending behind the telescope, I arrange a projecting plate which constitutes a horizontal sliding bed or rest *o* capable of lateral adjustment upon the upper portion of which the fulcrum or bearing *p* is formed and to which a graduated 90 batter rod *q* is mounted so that it comes to rest on the ledge of the foundation plate, and on the same foundation plate a graduated batter quadrant *r* is mounted, a set 95 screw and clamp *s* being fitted to the batter rod so that when the latter is set at any desired angle it can be clamped on to the aforesaid quadrant. An extension *t* on the horizontal bed is also graduated, the zero line for the graduations of the extension being in alinement with the vertical center line of the pillar. The divisions of all the 100 105 110

graduations are equally spaced and are divided off to a fineness sufficient to enable them to be read with the naked eye. The space between the zero of the rod or extension of the horizontal bed and a vertical alinement or vertical plane of the axis of the bed is equivalent to one-half of the width of the road in the case of the cutting of an embankment.

10 The operation of my invention is as follows: The levels of the line of road or railway having been set out with center pegs, the vertical pillar is set up above the center line of the track either resting upon the ground or upon a portable staff of known height to which it may be clamped if so desired or the operator may hold the instrument in his hand. The vertical slide block *c* is elevated or depressed to any convenient position and the height is read on the vertical graduated scale.

One of the functions of the instrument is to ascertain within a few minutes the exact position of the top of the batters of cuttings or the toes of fillings before earthworks are proceeded with, thus doing away with a lot of contour drafting.

According to the nature of the soil the batter of an earthwork may require a slope 30 of any ratio between two to one and one-fourth to one and the operator sets the batter rod to the slope which in his judgment and experience he considers most suitable.

The batter rod is now clamped to the batter quadrant at an angle corresponding to the required slope according to the nature of the soil. The slide or block *c* is next adjusted vertically from zero to the value in depth of earthwork, corresponding to the center level peg. The sight is next taken through the telescope to a mark corresponding in height from the ground to the height of the axis pin *f*. When this has been done the operator reads off the graduation on the telescope extension at the point where it intersects the graduated batter rod which gives the distance for that angle. The field peg is then inserted at the position so located, and at the same time the length of batter may be read off and recorded in the field book, as well as the length recorded on the extension rod.

The sight may be taken from any point on the formation provided the distance from 55 the point to the edge of the formation is adjusted on the sliding bed. It is, however, usual in railway and road work to take observations from over or between pegs placed on the center line. The staff (not a graduated one) as described is held at nearly the distance required and by its aid the true angle of surface slope is ascertained. Then the distance from that angle is read off the graduated telescope extension and measured off provided the ground slope remains

the same at the new distance. In fact the actual ground measurements must be the same as those found in the instrument.

These operations are completed in about as many seconds of time as it takes minutes 70 by the present method of dummy level and theodolite and pop with staff and tedious calculations are avoided and the chances of error are in consequence reduced to a minimum. The device saves an immense amount 75 of drawing material and labor for, having accurate values of cross-sections, the cubic contents may be arrived at almost immediately by adding two consecutive + sections, multiplying by the distance between them 80 and halving the result.

Referring to Fig. 7, if the surface is a bit irregular by keeping the telescope clamped at the slope *p p'* the depth or height of *w* can be measured and the distance from *p* and then the contents calculated on the spot may be applied to the contents of the regular quadrilaterals + or -.

For a filling when the angle of surface slope has been ascertained, the same angle is 90 set on the opposite side of the zero, that is the angle of declivity becomes one of acclivity and vice versa before the length of slope required may be read off. The instrument may be turned upside down as the 95 level claimed is shaped to allow of the bubble coming to zero in both positions. An embankment may be likened to a cutting upside down. Instead of reversing either the instrument or the earthwork, reverse the 100 angle and the same object is attained.

If the cross sections are to be plotted the vertical readings should also be recorded in the field book for which purpose it is only necessary that the telescope extension be 105 placed at right angles to the batter rod to obtain the readings.

Referring now to the graduations on the extension of the horizontal bed, it will be observed that the zero point or graduation 110 does not correspond vertically with the axis *f*. The space between the zero of the rod and the vertical alinement with the axis is equivalent to one half of the width of the road in the case of a cutting or an 115 embankment.

In the illustration I have allowed for a standard road of six feet in width, but for wider roads the extension must be adjusted by lateral movement to suit the extra width. 120

Referring now to Fig. 6 of the drawings I have illustrated by diagram the relative functions of the working parts of my instrument. In the diagram the line *n* corresponds to the telescope extension and represents the natural surface of the earth and the line *a* corresponds to the vertical pillar. The distance from the sliding horizontal *o* to the axis *f* represents the value of the center line level peg. The graduated batter 130

rod q is set according to practice as previously described. The horizontal distance from the intersection of the vertical line to the axis of the batter rod represents half 5 the width of the formation level and the dotted line n' represents the telescope extension when placed at right angles to the batter rod.

The formula for calculation of areas for 10 plotting sections may be stated as follows:—

Multiply half formation width by depth given (on vertical pillar, *i. e.*, from f to o) and add the result to the length of batter 15 multiplied by the perpendicular of the telescope extension (from axis to intersection of batter rod) and divide by two. This operation being repeated on the other side of the center peg and the totals added together will give the contents of the whole cross- 20 section.

The instrument which I have described in the specification is designed for practical field work. For draftmanship a substantially similar tool is constructed but without the level as the level would be represented in the plan by a horizontal line thus rendering the telescope portion unnecessary. Such a tool would be suitable for drafting 25 and calculating the slopes and areas of the 30 various cross sections.

I claim:

1. A cross-sectional clinometer including a vertical pillar having graduations, a member pivoted to the pillar and having a 35 graduated extension projecting from the pillar, a vertically adjustable slide mounted on the pillar and coöperating with the graduations thereof and a horizontally adjustable member carried by the slide and 40 provided with a graduated extension and a batter rod adjustably mounted on the said horizontally adjustable member.

2. A cross-sectional clinometer including a vertical pillar having graduations, a member pivoted to the pillar and having a graduated extension projecting from the pillar, a 45 vertically adjustable slide mounted on the

pillar and coöperating with the graduations thereof and a horizontally adjustable member carried by the slide and provided with a 50 graduated extension and a batter rod pivoted to and carried by the horizontally adjustable member, a graduated quadrant arranged to indicate the pivotal adjustment of the batter rod and means for securing the 55 batter rod in its adjustment.

3. A cross-sectional clinometer including a vertical pillar, a telescope pivotally mounted on the pillar and provided with a longitudinally disposed graduated extension, a 60 slide vertically adjustable on the said pillar, a horizontally adjustable bed carried by the slide and provided with a graduated extension and a batter rod pivotally mounted on and carried by the said bed. 65

4. A cross-sectional clinometer including a vertical pillar provided with a slot and having graduations, a level mounted on the pillar, a telescope pivotally connected to the pillar and having a graduated extension, a 70 vertically adjustable slide mounted on the pillar and having clamping means operating in the said slot, a horizontally adjustable bed slidably interlocked with the said vertical slot, and provided with a graduated extension and a batter rod pivotally mounted 75 on the said bed.

5. A cross-sectional clinometer including a vertical pillar, a level mounted on the pillar, a telescope having a graduated extension, a slide vertically adjustable on the pillar, a horizontally slide bed mounted on and carried by the said slide and provided with a graduated extension, a batter rod pivotally mounted on the said bed and 80 graduated quadrants mounted respectively 85 on the pillar and on the bed and associated with the telescope and the batter rod to indicate adjustments of the same.

ARTHUR JOHN HENRY ARTHUR.
